UNITED STATES PATENT OFFICE

VALENTIN LORENTZ, OF DRESDEN, GERMANY, ASSIGNOR TO UNITED CIGARETTE MACHINE COMPANY AKTIENGESELLSCHAFT, OF DRESDEN, GERMANY

PROCESS AND DEVICE FOR IMPROVING CIGARETTES

Application filed September 21, 1927, Serial No. 220,978, and in Germany September 23, 1928.

The invention relates to a process for improving or refining cigarettes. It has been found that the cigarettes manufactured in the usual way are liable to contain dust in 5 more or less considerable quantities which first is prejudicial to the taste and the hygienic quality of the cigarettes. According to the present invention this inconvenience is obviated by that the dust is removed from 10 the cigarettes preferably while these are manufactured or packed. The removal of dust may be accomplished either by means of a separate dust removing appliance or by that the conveying means transporting the 15 cigarettes during manufacture or packing one by one or in smaller or larger quantities are provided with suitable means, for instance of such a kind that they remove the dust particles by blowing an air current 20 through the cigarettes moving continuously or by steps.

The drawing represents several arrangements showing by way of example how the idea, upon which the invention is founded, 25 may be realized.

Figs. 1 and 2 are a side elevation and a cross section respectively of a device which removes the dust from each of the cigarettes, while they are conveyed over a fluted drum, 30 whereas

Figs. 3 and 4 are partial views of similar devices which repeatedly remove the dust from the cigarettes conveyed one by one.

Fig. 5 is a cross section through the ring of 35 the fluted drum according to Fig. 3 and

Fig. 6 is the view of a device which removes the dust from the cigarettes while they are conveyed over a simple belt.

Fig. 7 shows a device in which several 40 cigarettes contained in the flutes of a conveying drum are freed from dust at the same time and

Fig. 8 is a similar device in which the cigarettes are disposed in trays in lieu of flutes, whereas

Fig. 9 represents a device intended for removing the dust from the cigarettes while they are conveyed towards a packing appliance.

Fig. 10 shows a receptacle adapted to re-

ceive the cigarettes, when the removal of the dust is accomplished independent of special conveying means.

In Figs. 1 and 2, 1 is a fluted drum or conveying drum of known design which is driven continuously or by steps by means of a shaft 55 2. Above the fluted drum 1 there is arranged a hopper 3 filled with any convenient number of cigarettes which drop into the flutes while the fluted drum 1 is revolving and which, 60 after a certain angle of revolution, get upon a conveying belt 5 which brings them to further treatment. At any point whatever of the ring of the fluted drum 1 filled with cigarettes there are arranged axial pipes 6 or the like through which compressed or 65 suction air is fed so that it passes through the cigarettes 4 conveyed one by one between the free ends of the pipes 6 and removes from the cigarettes the dust contained. Lest the 70 cigarettes should be blown from the drum flutes or the tobacco from the cigarette husks while the dust is removed, the pipes 6 are provided with gauze or sieves 7 at their free ends disposed at the sides of the fluted drums 75 so that the dust only may pass freely.

The instances of execution shown in Figs. 3 and 4 chiefly distinguish themselves from the dust-removal devices according to Figs. 1 and 2 by that compressed or suction air is passed 80 through the cigarettes more than once in such a way that in Fig. 3 several pipes 6 are distributed over the circumference of the drum whereas in Fig. 4 the pipe 8 through which the air is passed extends over several flutes of 85 the drum 1 so that in both cases the cigarettes are freed from dust, continuously or by steps, over a longer travel than in the former cases. With the arrangements according to Figs. 3 and 5 the cigarettes to be freed from dust are retained, except by the gauze 7, by springs 9 engaging with notches 10 of the teeth 11 and resting on the cigarettes 4. When these springs 9 are provided the wire gauze 7 may eventually be dispensed with.

The devices described above may be separate dust-removal appliances working independently of the cigarette machine proper so that the cigarettes are fed to them for the dust removal only. As a rule however it is 100

preferable to dispose the dust-removal devices directly behind the cigarette machine proper, for instance in such a way that the cigarettes drop from the cigarette distributor 5 or the cigarette machine directly into the hopper 3 in order to be received by the fluted drum 1.

Fig. 6 shows an arrangement in which the dust is removed from the cigarettes 4 while 10 they are conveyed over an ordinary conveyer belt 12, their cross section being rectangular in this case, the width of the pipes is proportioned in such a way that the dust is removed at the same time from several cigarettes 15 conveyed one by one. As in the instances of execution described above the ends of the pipes 13 are covered with gauze 7 in order to prevent the cigarettes from being blown out.

20 The instances of execution shown in Figs. 7 to 9 distinguish themselves from the other instances already described by that the cigarettes to be freed from dust are not conveyed one by one but in small clusters. In 25 the appliance represented by Fig. 7 the cigarettes are conveyed by means of a fluted drum 15 similar to the fluted drum 1 in Figs. 1 to 4, but the flutes of drum 15 are so dimensioned that it is able to receive a smaller 30 or larger number of cigarettes. In this case the dust-removal device consists, in accordance with Figs. 1 to 3, in pipes 6^a with gauze covers 7 the diameter of which is larger than that of the flutes 16 so that when the latter 35 move along the ends of the tubes 6^a all cigarettes 4 contained in the flutes are freed from dust at the same time. The appliance may be an independent dust removing device or form a part of the cigarette machine. With 40 the arrangement shown in Fig. 8 the fluted drum for conveying the cigarettes 4 is replaced by trays 17 fastened to a horizontal conveyer belt 18. The dust removing pipes of this arrangement may be disposed as in 45 Fig. 7 or corresponding to one of the foregoing instances of execution.

Fig. 9 shows an arrangement by which the cigarettes 4 are freed from dust while they are treated in a packing appliance. To this 50 end there are disposed at the side of the conveying chain 20, running over a sprocket wheel 19 and intended for bringing the cigarettes 4 to the boxes or the like, certain means for feeding compressed or suction air, for instance rectangular pipes 13^a which are so proportioned that all cigarettes pertaining to one packet are freed from dust at the same time.

60 In order to perform the process, to which this invention relates, besides the contrivances already shown numerous other arrangements are possible by which dust is removed from the cigarettes while they are worked 65 in the cigarette machine or treated in the

packing device, or in a separate dust removing device.

The way of feeding and carrying of the compressed or suction air is optional; for instance for repeated dust removal there may be applied alternately compressed and suction air or the direction in which air is blown in or sucked may also alternate etc. 70

An instance of execution in which the improvement and the removal of dust is accomplished by a separate contrivance independent of special conveying appliances is shown by way of example in Fig. 10. Here the cigarettes 4 are contained in a special receptacle 22 both sides of which 23 and 24 are 75 covered with a material permeable to air, e. g. sieves. The receptacle filled with cigarettes is inserted by hand in a compressed-air piping which may pass compressed air either from one side only or alternately from both 80 sides. Of course it is possible to use compressed or suction air as the case may be. 85

I claim—

1. A device for improving cigarettes comprising in combination, pipings having open ends for feeding an air current, pipings having open ends arranged oppositely to the open ends of the first mentioned open ends and adapted to receive and discharge the said air current and conveying means adapted to mechanically pass the cigarettes between the open ends of said pipings so that the air current passes through them in a lengthwise direction. 90

2. A device for improving cigarettes comprising in combination, pipings having open ends for feeding an air current, pipings having open ends arranged oppositely to the open ends of the first mentioned open ends and adapted to receive and discharge the said air current, conveying means adapted to mechanically pass the cigarettes between the open ends of said pipings so that the air current passes through them in a lengthwise direction, and means arranged on said conveying means and preventing the cigarettes from lengthwise movement while they are between the said pipings. 100

3. A device for improving cigarettes comprising in combination, pipings having open ends for feeding an air current, pipings having open ends arranged oppositely to the open ends of the first mentioned open ends and adapted to receive and discharge the said air current, conveying means adapted to mechanically pass the cigarettes between the open ends of said pipings so that the air current passes through them in a lengthwise direction, and means arranged between the open ends of said pipings and said conveying means adapted to being passed only by the air current and the dust contained therein and preventing the cigarettes from being moved in a lengthwise direction. 115

4. A device for improving cigarettes, com- 120

130

prising in combination, means for feeding an air current, means for receiving and discharging said air current and being arranged opposite to said first means and conveying means adapted to mechanically pass the cigarettes between said first mentioned feeding and discharging means so that the air current passes through them in a lengthwise direction.

10 5. A process for improving cigarettes consisting in passing an air current alternately in both directions in a lengthwise direction through them.

15 In testimony whereof I have affixed my
signature.
